ANODE

Alexander Henderson, Detroit, Mich., assignor to
The American Brass Company, Waterbury,
Conn., a corporation of Connecticut.

Application July 31, 1931, Serial No. 554,285

2 Claims. (Cl. 204—4)

This invention relates to an anode for electroplating, and has for an object to provide an anode which will give a higher efficiency and better distribution of corrosion during the plating process.

It is also an object to provide an anode in which there is a large external surface in contact with the electrolyte in proportion to the amount of metal used in the anode.

10 Another object of the invention is to provide an anode in which at no time during the life of the anode will the surface exposed to the electrolyte be reduced to any marked extent, and thus the surface exposed to the electrolyte will be substantially constant or at least be reduced only a relatively small extent during the entire life of the anode. In other words, the material is so located that as it corrodes or is eaten away the surface exposed to the electrolyte is not materially or objectionably decreased.

25 A further object of the invention is to provide an anode in which the scrap or waste is reduced to a minimum or practically nothing, and which for a given amount of active metal less metal is required to be suspended in the plating tank than is the case with ordinary anodes, and which also requires less metal to be carried in stock.

30 A further object is to provide an anode which for the same amount of efficient surface corrosion will weigh not more than approximately one-half of solid anodes of the same shape and dimension, and therefore for a given surface exposure to the electrolyte the user of the anode will require only approximately one-half or less of 35 weight of metal to equip a plating tank.

40 Other and further objects of the invention will appear from a more detailed description of the invention taken in connection with the accompanying drawing forming a part of this specification.

In this drawing:

Fig. 1 is a side elevation of an anode constructed according to this invention;

Fig. 2 is an end view thereof; and

45 Figs. 3 and 4 are end views on a somewhat smaller scale of similar anodes of a somewhat modified construction.

50 In electroplating it is desirable that a large surface of the active metal be exposed to the electrolyte, and it is also desirable that the amount of this surface be maintained as uniform as possible for satisfactory operation. Various attempts have been made to secure these results, but the anodes so produced have been complicated and expensive, and furthermore they did

not secure the results to the extent desired. With my improved anode I secure both these results as well as other advantages, and in proportion to the amount of metal in the anode secure a large corrosion surface exposed to the electrolyte, and maintain this exposed surface substantially constant, or at least reduce its variation to a minimum during the useful life of the anode. I secure these improved results and advantages by making the anode in the form of a hollow tube, 60 preferably oval in cross section as this gives a better distribution of the metal with more uniform corrosion during the plating operation, and also provides a better distribution or placing of the exposed surface for greater efficiency and 65 uniformity in the plating operation.

Referring to the accompanying drawing, in Figs. 1 and 2 the anode 10 is shown as a hollow tube of oval shape in cross section with the walls of substantially uniform thickness throughout. 70 It can be suspended in the electrolyte by any suitable means, that indicated involving providing the opposite side walls with transverse openings 11 to receive a rod to pass through the eye 12 of the suspending hook 13 to hook over the usual conductors or buss bars 14 and conduct the necessary current to the anode. The walls of this anode are continuous and the anode may be formed in various ways. It is preferred that the metal be worked to give a uniform and dense texture as this provides better operation in the plating process. Thus a round billet may be longitudinally pierced and rolled to form a tube as in the Mannesmann process, which not only forms a tube from the billet but works the metal into a 75 dense uniform texture. The tube thus formed can be given the desired oval shape by passing it through rolls having grooves of the desired shape, or by drawing the tube through suitably shaped dies. This provides a wrought anode in which 80 the metal is dense and worked so that it is of 85 uniform texture and is a better anode.

It is however not necessary that the wrought anode be worked by piercing and rolling as described, but the metal may be worked by rolling into flat strips or slabs and then folded into the desired shape by passing through rolls or suitable dies, thus producing anodes as illustrated in Figs. 3 and 4. As illustrated in Fig. 3 the strip is folded to form an oval tube 15 with the abutting edges coming together at 16 in one of the edge portions of the tube. In Fig. 4 the strip is folded to form a tube 17 with the abutting edges coming together at 18 in one of the flatter sides of the tube. These 90 seams may be left as merely abutting joints or they 95 100 105 110

may be welded or brazed as desired. In either case whether pierced as in Figs. 1 and 2 or folded as in Figs. 3 and 4, it will be evident that there is produced a wrought anode in which the active metal 5 has a smooth outer surface where it is in contact with the electrolyte, and the metal is all located where it can be used effectively. Although it is preferred that the tubes be worked and of oval shape in cross section as shown, they need not 10 necessarily be so, although this is the much preferred construction. The tubes can be cast in this shape and they can be given different shapes in cross section, but the wrought or worked tube is preferred as giving a metal of denser and more 15 uniform texture, and the oval shape is preferred as it gives a more uniform corrosion of the metal throughout the exposed surface. In square, rectangular or similar shapes there is more corrosion at the sharp corners than at other portions of the 20 surface, and therefore the eating away of the metal is not uniform.

In the use of solid anodes it will be evident that after a given amount of use the surface exposed to the electrolyte is reduced to such an extent as 25 to greatly decrease the efficiency of the anodes. It is therefore common practice to discard the central portion of the anodes after a given reduction of the exposed surface, and replace them with new anodes having the desired surface. This 30 involves a large amount of scrap or waste which can of course be cleaned and remelted and put into new anodes, but this involves handling of considerable metal, and metal which is useless in the metal plating process. With my improved 35 anode however, there is no central core of any kind to be discarded and it will be evident that all or practically all of the metal can be used without materially decreasing the surface exposed to the electrolyte, or at least without decreasing this exposed surface to an objectionable extent. In 40 other words all of the metal of this anode is located at or adjacent the outer or exposed surface of the anode, and for a given amount of metal there is a smaller proportional decrease in the exposed surface in contact with the electrolyte as 45 the metal corrodes, and therefore the entire anode can be used for the plating process without decreasing the exposed surface to such an extent as to be objectionable or greatly reduce the efficiency 50 of the plating process. Thus for example if the oval opening through the tube represents substantially one-half the cross sectional area within the outer outline of the tube, then it will be evident that this improved anode will weigh only

about half as much as a solid anode of the same outside dimensions, and therefore if the outline of the opening represents the smallest exposed surface which could be used efficiently then the entire metal of this new anode can be used efficiently and there will be no scrap or waste of metal. Therefore at no time during the life of the anode will the surface exposed to the electrolyte be reduced to a marked or objectionable extent because for the same amount of active 80 metal the exposed surface will remain substantially uniform, or at least will not be reduced to less than 75 or 80 percent of the original surface.

This is important in other ways, as it will be evident that for the user to equip a plating tank with the same amount of useful metal only about half the weight of metal is required to equip the tank of what would be required with the old solid anodes. This also means a considerable saving in the weight of metal carried in anodes in stock. 90 This further effects a considerable saving in handling as there is less metal to be handled in the anodes themselves, and there is practically no scrap. It will of course be obvious that the anodes can be made of various sizes and the ratio of the 95 outside dimensions or surface with respect to the inside dimensions or surface may be determined depending on the amount of reduction of the surface exposed to the electrolyte which is permissible in the plating operation without an objectionable decrease in efficiency and uniformity of plating. It will of course be understood that these anodes can be made of any metal or composition desired for the plating operation involved, such for example as copper, nickel, chromium, brass, 100 silver etc.

Having thus set forth the nature of my invention, what I claim is:

1. A soluble anode for electroplating comprising a hollow tube of active metal of oval shape 115 in cross section, the opening through the tube being also of oval shape, and both of said ovals being of similar shape and direction.

2. A soluble anode for electroplating comprising a hollow tube of active metal of oval shape 120 in cross section, the opening through the tube being also of oval shape, both of said ovals being of similar shape and direction and the inner oval being of a size that the tube contains not more than approximately one half the metal which would be 125 contained in a solid bar of the same cross section as the tube.
